ELECTROMAGNETIC HORN

Wilmer Lanier Barrow, Newton, Mass., assignor
to Research Corporation, New York, N. Y., a
corporation of New York

Application January 9, 1939, Serial No. 249,910

20 Claims. (Cl. 250—11)

The present invention relates to electromagnetic horns.

To avoid circumlocution of language, when the horn is recited in the claims as having "exciting or absorbing means," it will be understood generically that either the horn is provided with either an exciting or absorbing antenna or the like, or else that a hollow-pipe transmission system or the like is connected to the throat of the horn. When "exciting or absorbing" is recited in the claims as positioned in the throat of the horn, it will be understood that an exciting or absorbing antenna or the like is positioned in the throat of the horn.

It is by no means true that any horn will transmit or receive any wave, and an object of the present invention is to assure the production near the mouth of the horn of a wave of a desired type, such as the $H_{0,1}$ or $H_{1,0}$ wave.

On the other hand, a plurality of different types of horn waves may be generated, depending upon the configuration of the exciting means in the throat of the horn, or upon the nature of the waves delivered there by a hollow-pipe transmission system, and also upon the flare angle ϕ_0 and the cut-off length ρ_0 from the apex to the throat, or small or reflecting end, or the back of the horn. Special cases may arise wherein several wave-types may be used simultaneously. In many applications, however, a single wave should obtain near the mouth of the horn, as the radiation pattern will be distorted by the presence of other waves.

A further object, therefore, is to exclude waves of other types than those desired.

To the attainment of these ends, it is desirable to position the exciting or absorbing means properly, or properly to design the size of the throat and the radial length of the horn, or both.

Another object is to provide a horn having a predetermined performance.

A further object is to provide quantitative curves to facilitate the design of such horns.

Other and further objects will be explained hereinafter and will be particularly pointed out in the appended claims.

The invention will now be described in connection with the accompanying drawings, in which

Fig. 1 is a perspective, partly broken away, of a sectoral electromagnetic horn embodying the invention, and fed by a hollow-pipe line;

Figs. 2 and 3 are similar perspectives of modifications;

Fig. 4 is a diagrammatic perspective of a sec-

toral horn, disposed in Cartesian and cylindrical systems of co-ordinates, and carrying symbols useful in describing the invention;

Fig. 5 is a plot of two curves showing the relation between the flare angle ϕ_0 and the cut-off length ρ_0 of the horn from the apex to the throat, the cut-off length ρ_0 being represented in terms of the wave length λ ;

Figs. 6 and 7 are plots of further curves to be described more fully hereinafter; and

Figs. 8 and 9 are views similar to Figs. 1 and 4, respectively, of a conical horn.

In Figs. 1 to 4, there is illustrated a horn 16 of rectangular cross section, flaring smoothly and continuously from the throat to a mouth or aperture or large end of the horn, at its front. The principal or central axis of the horn extends between the smaller and larger ends of the horn. At its throat, it is shown connected to a hollow-pipe transmission system comprising an elongated hollow pipe or tube body portion or section 18 that is connected to the throat of the horn so as to extend over any desired distance from the horn, to the left, as viewed in Figs. 1 to 4.

The horn may be constituted of a formed sheet of conducting material, like metal, such as copper or aluminum, or it may be constituted of other material if its inner wall is otherwise rendered a conductor of the said waves. The hollow-pipe body portion 18, to which the horn 16 is connected, may be of any desired material, conducting or dielectric, or it may otherwise be provided with an inner conducting wall. It may contain air or other gas, or it may be evacuated. If the body portion 18 is constituted of a metal pipe, the flared-out continuation may constitute a conducting extension of the body portion 18. If the horn 16 is of simple rectangular shape, the pipe portion 18, from which it flares out, may be likewise rectangular. The horn may, however, have abrupt changes. Screen or other semi-open construction may also be employed. As dielectric supports and insulators are not required in any region of intense field, dielectric losses are low.

Two of the sides, shown as the top and bottom sides, may be substantially parallel, and the other two sides flared, as illustrated in Figs. 1 and 3, or the horn may be pyramidal, with the sides of the horn flaring in four oppositely disposed directions, as illustrated in Fig. 2. The horns of Figs. 1 and 3 may be described as of sectoral shape, and the horn of Fig. 2 may be termed pyramidal. The advantages of the sectoral shape are described in

my application, Serial No. 227,183, filed August 27, 1938. Horns provided with straight sides in longitudinal cross-section, as illustrated, are economical and easy to construct. The invention is, however, applicable also to horns of other shape, including circular or round in cross-section, and to sides of varying flare, such as exponential or hyperbolic.

The waves inside these horns, at a distance several wave-lengths from the throat, are governed, among other things, by the dimensions of the sides and the flare angle ϕ .

The horn of the present invention may be used for transmission or reception of ultra-high-frequency electromagnetic waves. In transmission, electromagnetic energy, transmitted through the interior of the pipe or tube 18 from a projecting metal exciting or absorbing antenna rod or other energy-translating apparatus 14, is delivered to the throat of the horn and propagated through the interior of the horn to the mouth as "horn waves." At the mouth, substantially all of this energy is radiated into free space as ordinary radio waves. The horn thus constitutes a directive electromagnetic radiator.

In receiving, a similar, but reverse, process takes place, the electromagnetic waves being received by the horn 16, and communicated to a receiving system (not shown).

The rod 14 is shown in Fig. 1 disposed approximately centrally in the hollow pipe 18, substantially at right angles to the axis of the horn, but it may be disposed unsymmetrically in the horn, to give a modified directive pattern for the radiant energy.

Sending apparatus (not shown) may be connected to a coaxial-line system 10, 12, or to a parallel-wire system, or to any other desired connecting system. The conductor 12 may be extended into the bell of the horn or the tube 18, either parallel to the top and bottom walls, as in Fig. 3, or at right angles thereto, as in Figs. 1 and 2, to constitute the antenna 14.

Different types of horn waves, and combinations of the same, may be separately excited and propagated within the horn, or absorbed by the horn, by properly arranging the exciting rod or rods in or out of the throat of the horn, both as to the position of, and the current in, the rod or rods.

One of the most important modes or wave types is the lowest-order transversely polarized horn wave $H_{0,1}$, with the electric vector mainly parallel everywhere to the vertical direction, obtained with an exciting rod 14 transverse to the axis and in the vertical plane. Another important mode or wave type is the $H_{1,0}$ wave. These two wave types are probably the best for sending a single beam of radiant energy and are the waves most naturally adopted for receiving. For beam transmission, a horn of rectangular cross section perpendicular to its principal or central axis, and the orientation of the exciting rod perpendicular to this axis, offer certain features, among them the important feature of a radiated linearly polarized space wave. The rectangular shape, furthermore, permits independent control of the width of the radiated beam in the horizontal and vertical planes.

Beams transmitted from directive antenna systems are usually accompanied by small amounts of radiation in directions other than those intended. These small amounts of radiation are referred to as secondary lobes. Beams radiated from sectoral horns may be remarkably free from

secondary lobes. For this reason, the use of sectoral horns is particularly advantageous in certain kinds of applications where the shape of the beam plays an essential role in the operation.

5 In the blind-landing of airplanes, for example, it is desirable, not only that the beam be very sharp, but also that it be peculiarly free from secondary lobes. In one such application, a smooth straight-line intersection is formed between two overlapping beams; systems of this type are commonly referred to as "equal-signal" systems. Horn radiators can provide such smooth overlapping beams without waviness or spurious components that would affect the straightness of 10 this path of intersection. No other types of antenna have been found to produce so smooth beams with such small secondary lobes. Patterns of this character are useful also in other applications, such as direction-finding and obstacle-detection.

15 Though the analysis will be hereinafter given in connection with sectoral horns, it applies also very approximately to horns that are somewhat pyramidal in which the two substantially parallel sides are not strictly parallel but diverge to some extent. The term "substantially sectoral" will be employed in the claims to include somewhat pyramidal horns of this nature.

In Figs. 1 and 3, as before described, the horn 30 16 is shown excited by means of a hollow-pipe transmission line 18, connected to the throat of the horn, with the translating apparatus positioned in the pipe 18, at the rear of the throat of the horn. The antenna then first excites

35 waves in the hollow pipe, which are transmitted through the pipe 18 to the horn, and thence into free space as ordinary radio waves. It is sometimes desirable, however, as explained in my application, Serial No. 240,545, filed November 15,

40 1938, that the translating apparatus be positioned directly in the throat of the horn, as illustrated in Fig. 2, in order directly to excite the horn itself, without the use of a hollow-pipe transmission line. It then operates efficiently to receive

45 substantially all of the incident energy, when used as a receiver; or, when used as a transmitter, to excite waves of the horn type, and thereby to radiate a beam of character appropriate to the horn rather than to the apparatus and the antenna itself. With the apparatus in the throat, furthermore, the horn has smaller physical dimensions than when connected to the hollow pipe.

50 The hollow-pipe method of Figs. 1 and 3 is mainly useful for wave-lengths less than about 20 centimeters, and the method of Fig. 2, involving the positioning of the antenna or other energy-translating means directly in the throat of the horn, is applicable to longer waves. Substantially the same radiation pattern may be produced with either arrangement.

The invention is not, of course, limited to the use of an exciting or absorbing rod 14. Other radiating or absorbing means, such as a vacuum tube, may also be employed, as described, for example, in the said application, Serial No. 240,545, filed November 15, 1938. As is also explained in the said application, Serial No. 240,545, optimum conditions may be obtained by adjusting a

70 piston (not shown) at the back or throat of the horn, thus to resonate or tune the throat of the horn, thereby rendering the throat of the horn more responsive to a particular frequency or a narrow band of frequencies than to other frequencies, and also in other ways.

Symbols that will be used in this specification will be understood by reference to Fig. 4. The lower of the two parallel sides of the horn of Fig. 1 is here assumed to lie in the XZ plane, with its non-parallel or flaring sides, extended, intersecting on, and making equal angles with, the Y axis. The system may be regarded as symbolizing also cylindrical co-ordinates y , ρ , and ϕ . The upper parallel side of the horn is parallel to the XZ plane, and at a distance a therefrom. It is assumed that the throat of the horn is disposed along a vertical cylindrical surface having a radius ρ_0 and with its axis coincident with the Y axis. The non-parallel sides, each of length $\rho_1 - \rho_0$, are symmetrically disposed in planes perpendicular to the XZ plane, forming with the XY plane a dihedral angle equal to $\phi_0/2$, and parallel to the lines of electric intensity of the waves propagated within the horn. The horn is regarded as having a forward direction in the positive direction of the X axis. The horizontal length of the mouth or aperture of the horn is assumed to have a value b , and the corresponding length of the throat to have a value D_0 . The symbols illustrated in Fig. 4 have, therefore, the following meaning:

- ϕ_0 represents the flare angle of the horn illustrated in Fig. 1;
- b represents the horizontal dimension of the mouth or aperture of this horn, or the distance between the opposite horizontally disposed sides of the horn, at the mouth of the horn;
- a represents the corresponding vertical dimension, at right angles to the horizontal dimension, or the distance between the opposite vertically disposed sides of the horn, at the mouth of the horn. This vertical dimension is parallel to the lines of electric intensity of the waves propagated within the horn;
- ρ_1 represents the radial length of the horn, measured along one of the flaring sides, from the point or apex of the horn to the mouth or aperture; and
- ρ_0 represents the cut-off length, from the said apex to the free end of the throat of the horn.

These symbols will have approximately the same or corresponding meanings in the case of pyramidal horns two of the opposite sides of which may be more or less parallel. It is convenient to measure the lengths a , b , ρ_0 and ρ_1 in terms of the wave-length λ ; they may, therefore, if the same unit of length be used for all dimensions and for the wave-length λ , be represented by the symbols

$$\frac{a}{\lambda}, \frac{b}{\lambda}, \frac{\rho_0}{\lambda} \text{ and } \frac{\rho_1}{\lambda}$$

The space wave radiated by the horn in beams of different configurations, and the response of a receiving horn to waves arriving at different space angles, depends on the shape of the horn in all cross sections, and the configuration of the exciting system at the throat, or of the wave delivered there by the hollow-pipe transmission line. It depends also on the flare angle ϕ_0 and the cut-off length ρ_0/λ .

In general, there are two distinct groups of waves: E-waves, having a radial component of electric intensity, but no radial component of magnetic intensity, in the horn; and H-waves, having a radial component of magnetic intensity, but no radial component of electric intensity, in the horn. Two subscripts are needed to define the waves of different orders. The sub-

scripts n and m are used, each representing a positive integer denoting the number of half-sinusoidal variations in the field between the top and bottom and the two side walls, respectively. Thus, we have the $H_{n,m}$ and the $E_{n,m}$ types of waves.

For most applications of the horn, the H-waves are employed, particularly the two waves of lowest order, $H_{0,1}$ and $H_{1,0}$. The reason for this choice is that the configuration of the field of these waves inside the horn is such as to produce substantially single-lobe beams of linear polarization in the radiated waves. Both waves have constant phase on cylindrical surfaces about the axis within the horn.

As before explained, it is an object of the present invention to design the throat or the exciting means 14, or both, so that a desired wave, such as either an $H_{0,1}$ or $H_{1,0}$ wave, and also, in cases, the desired wave only, shall exist in the horn, when used for transmitting; or so that the horn shall be responsive to the desired wave, such as either the $H_{0,1}$ or $H_{1,0}$ wave, or the desired wave alone, when used for receiving.

The $H_{0,1}$ wave may be excited by the current-carrying antenna rod 14 in the throat disposed parallel to the Y axis of Fig. 4, as shown in Fig. 2, or by feeding an $H_{0,1}$ wave into the throat from the rectangular hollow pipe 18, as shown in Figs. 1 and 3.

The properties of the $H_{0,1}$ and the $H_{1,0}$ waves will not be further described herein. A description thereof may be found, for example, in my copending application, Serial No. 249,005, filed January 3, 1939, which makes reference to a paper by L. J. Chu and W. L. Barrow, entitled, "Electromagnetic waves in hollow metal tubes of rectangular cross section," Proceedings of the Institute of Radio Engineers, vol. 26, No. 12, December, 1938, commencing at page 1520, a paper by W. L. Barrow, entitled, "Electromagnetic-horn radiators," Union Radio Scientifique International, No. 79, p. 277, containing a revision of a paper presented at the Joint Meeting of the said Union and the Institute of Radio Engineers, at Washington, D. C., April 30, 1938, a paper by W. L. Barrow and L. J. Chu, entitled, "Theory of the electromagnetic horn," Proceedings of the Institute of Radio Engineers, vol. 27, No. 1, January, 1939, commencing at page 51, and also a paper by W. L. Barrow and F. D. Lewis, entitled, "The sectoral electromagnetic horn," Proceedings of the Institute of Radio Engineers, vol. 27, No. 1, January, 1939, commencing at page 41.

It may be stated, however, that the electric field intensity E in the $H_{0,1}$ wave is everywhere parallel to the Y axis, at right angles to the direction of propagation. It is of uniform intensity in the direction of the Y axis, but it has a half-sinusoidal distribution in intensity along arcs concentric with the Y axis, between the two flared sides, at right angles to the direction of propagation. The magnetic lines lie in planes perpendicular to the Y axis, or parallel to the XZ axis.

The $H_{1,0}$ type of wave may be excited by the current-carrying antenna rod 14 disposed centrally in the throat parallel to the XZ plane, as illustrated in Fig. 3, or by feeding an $H_{1,0}$ wave into the throat from a rectangular hollow pipe.

In the $H_{1,0}$ wave, the electric lines of force lie along arcs concentric with the Y axis between the two flared sides; they have a uniform distribution along the arcs, but a half-sinusoidal distribution in the direction of the Y axis. The magnetic lines lie in planes passing through the Y axis.

Analysis, verified by experiment, has demonstrated that the attenuation of each wave is relatively large near the apex of the horn 16, which may be termed the attenuation region, but is progressively smaller at greater radial distances from the apex, which may be termed the transmission region. The attenuation region obviously involves small values of ρ , and the transmission region large values of ρ , and the boundary between the two regions is not definite. The attenuation region extends from the apex outward over progressively shorter portions of the horn for increasingly large flare angles ϕ_0 . For small flare angles ϕ_0 , therefore, the attenuation region extends over large distances from the apex. As the flare angle ϕ_0 is increased, the attenuation region shrinks and is confined substantially to the throat. The radial distance, from the apex radially outward, to which the region of relatively high attenuation extends, is progressively greater for waves of higher order than for waves of lower order.

Analysis, verified by experiment, has also established that there is a best position for the antenna rod 14, the horn 16 being carried back far enough toward the apex of the horn so as to attenuate undesirable waves and to send forth only the desired waves. In a horn of a given flare angle ϕ_0 , and for a given wave-length λ , therefore, a particular value for the cut-off length ρ_0 from the apex of the horn to the exciting antenna 14 may be adopted that will permit the $H_{0,1}$ wave to form and travel freely through the horn to be radiated into space from its mouth substantially unattenuated, but that will affect almost complete attenuation or filtration of higher-order waves $H_{0,3}$, $H_{0,5}$, etc. during propagation from the exciting antenna toward the mouth. Horns for the production of single-lobe smooth beams should have their cut-off lengths ρ_0 not too different from their optimum value. A proper value of ρ_0 to be associated with this optimum cut-off length ρ_0 may be chosen in accordance with the design of application, Serial No. 249,005, above-mentioned.

The relation between the flare angle ϕ_0 and the optimum cut-off length ρ_0 , measured in terms of the wave-length λ , for the high-attenuation region, for the $H_{0,1}$ and the $H_{0,3}$ waves, is illustrated in Fig. 5. The vertical cylindrical surface coaxial with the Y axis and at a distance ρ_0 therefrom represents the transition between regions of high attenuation, near the apex of the horn, to the region of free transmission, towards the mouth, for waves of the $H_{0,1}$ type. This corresponds to the curve $m=1$. The corresponding curve for the $H_{0,3}$ wave is indicated at $m=3$. For example, if the flare angle ϕ_0 is 20° , the exciting antenna 14 should be disposed approximately at a distance

$$\frac{\rho_0}{\lambda} = 1.8$$

from the apex, as given by the curve $m=1$. With the antenna 14 so disposed, waves of the $H_{0,1}$ type will be transmitted freely through the horn to the mouth, thence to be radiated into space. In this position, the antenna 14 will, at the same time, be within the attenuation region for the higher-order wave $H_{0,3}$, which will suffer extremely high attenuation in traveling through the small part of the horn until a distance from the apex is reached equal to

$$\frac{\rho_0}{\lambda} = \text{about } 5$$

which is high up, off the scale of Fig. 5. The intensity of this $H_{0,3}$ wave will, therefore, be so small that the wave will be substantially suppressed. As the same applies, in an increasing degree, to waves of still higher order, the $H_{0,1}$ wave will alone be permitted principally to reach the mouth of the horn. By so designing the throat of the horn, therefore, this $H_{0,1}$ wave may alone be obtained, and its appropriate smooth pattern radiated into space, which is very desirable in those applications where a smooth beam free from secondary lobes is desired.

The vertical dimension a of the horn affects neither the transmission characteristics of the $H_{0,1}$ wave nor the filtration of higher-order waves, except when a is very large compared to λ .

The above-described attenuation property of the horn provides for effective elimination of the higher-order waves. Let it be assumed, as an example, that the horn is excited for the $H_{0,1}$ wave by a small antenna 14 in its throat. As the current oscillates in the antenna 14, not only the $H_{0,1}$ wave, but also the higher-order waves, or spatial harmonics, $H_{0,m}$, are produced, which tend to propagate in the radial direction of the horn. In the vicinity of the throat of the horn, the field distribution, along an arc of the horn, is non-sinusoidal, because of the presence of these $H_{0,m}$ waves, and is so configured that the boundary conditions at the surface of the antenna 14 are satisfied. The magnitude of the fields of the higher-order waves are less than the magnitude of the field of the $H_{0,1}$ wave at the throat of the horn. For a given flare angle ϕ_0 , the range of the attenuation region is approximately proportional to the order of the wave. If the throat of the horn is appropriately near the horn apex, it may be in the transmission region of the $H_{0,1}$ wave, but it may be deep in the attenuation region of the higher-order waves ($m=3, \dots$). Most of the energy of the $H_{0,1}$ wave, therefore, will be freely transmitted out through the horn, but only a small fraction of the energy of the higher-order waves will travel as far as the mouth of the horn. The field distribution across the mouth of the horn, therefore, will be substantially free of the third and still higher-order waves; it will be a half-period sinusoid.

This may be understood from Fig. 7, embodying a number of curves plotted with the absolute value of the electric intensity E in the plane of the mouth of the horn as the ordinate, and the distance from the center of the mouth in the horizontal direction, parallel to the Z coordinate, measured in centimeters, as the abscissa, for different values of flare angle, $\phi_0 = 20^\circ, 40^\circ, 60^\circ, 80^\circ$. For $\phi_0 = 20^\circ$ and also for $\phi_0 = 40^\circ$, the distribution is substantially smooth and half-sinusoidal. For larger values of flare angle ϕ_0 , however, small irregularities, that are barely noticeable for $\phi_0 = 40^\circ$, become more and more pronounced until, when $\phi_0 = 60^\circ$, the distribution assumes a jagged saw-tooth form. The curves of Fig. 7 clearly illustrate this transition from a sinusoidal distribution for small flare angles ϕ_0 to a non-sinusoidal distribution that contains higher harmonic components of space variation for large flare angles ϕ_0 .

A corresponding series of radiation patterns, each in a plane substantially at right angles to the lines of electric intensity of the waves within the horn, and which may be found in Fig. 3 of the said Barrow paper in the Union Radio Scientific Internationale, show the effect of progressively increasing the flare angle ϕ_0 from $\phi_0 = 0$.

corresponding to an open-end hollow pipe, to a maximum value of $\phi_0=90^\circ$. The measurements were made at points in a circular path having a radius of 100 feet. The exciting antenna 14 was near the end of the hollow pipe 18, Fig. 1.

For $\phi_0=10^\circ$, the radiated energy is formed into a rather broad beam along the principal axis, and there is an irregular back-radiation curve. As ϕ_0 is made larger, the beam becomes sharper up to a value of ϕ_0 between 40° and 60° . At both these angles the beam is quite sharp. As the flare angle is made even greater, the beam becomes distorted by the appearance of secondary lobes, which push out into the principal lobe, broadening the beam as shown in Fig. 3G. For $\phi_0=90^\circ$, the secondary lobes are nearly as large as the principal lobe and the beam has been spread into a fan-shaped pattern with almost uniform radiation over an 80° sector.

Particularly noteworthy is the shape of the pattern for flare angles of 40° to 60° . There is only one lobe of small amplitude and the back radiation, which is of relatively small amplitude, is confined to a small angle. This unusually clean-cut pattern offers possibilities not easily obtained by other types of radiators. The practical absence of secondary lobes in the forward half-plane contrasts markedly with the presence of two or more such lobes of objectionably large amplitude in the patterns of conventional arrays of half-wave antennas and of parabolic reflectors.

A comparison of these radiation patterns with Fig. 7 shows that a sinusoidal variation of electric intensity across the mouth of the horn corresponds to a radiation pattern having a single principal lobe and secondary lobes of insignificant amplitudes. Non-sinusoidal distributions, on the other hand, occurring with flare angles ϕ_0 greater than 60° , correspond to irregular radiation patterns.

The irregular shape, involving the strong secondary lobes, may be attributed to the harmonic components of the distribution across the mouth of the horn. Even if the distribution had remained sinusoidal, however, there would have been a broadening of the main lobe for increasing flare angles ϕ_0 greater than about 50° , because, as the waves travel outward in the radial direction in the horn, a horn of large flare angle ϕ_0 can not concentrate the waves mainly in a single direction, even inside the horn.

The decrease in the width of the beam with increasing flare angle ϕ_0 up to ϕ_0 about 50° may be attributed to the increase in the horizontal dimension b of the mouth or aperture of the horn. Further increase in flare angle distorts the distribution across the mouth from the sinusoidal form, and causes actual widening of the beam and the appearance of secondary lobes.

When radiation by means of the $H_{1,0}$ wave in sectoral or slightly pyramidal horns desired, similarly, the higher-order $H_{3,0}$, $H_{5,0}$ . . . waves should be eliminated or filtered. Unlike the case of the $H_{0,1}$ wave just discussed, this wave is substantially independent of the flare angle ϕ_0 of the horn, but has a sinusoidal variation in the vertical or Y direction. In the sectoral horn, the transmission properties of the $H_{n,0}$ waves depend mainly upon the distance between the parallel, or top and bottom, surfaces of the horn. The attenuation is caused solely by decreasing the energy density as the area of the vertical cylindrical surface, coaxial with the Y axis, increases with ρ . The elimination of the higher-order waves may,

in this case, therefore, be achieved by adjusting the vertical horn dimension a . The $H_{1,0}$ wave will travel freely in the radial direction through the horn when a is greater than $\lambda/2$, but for free transmission of the $H_{3,0}$ wave, a must be greater than $3\lambda/2$, and so on for higher-order waves. To eliminate the higher-order waves, therefore, the dimension a should be slightly greater than $\lambda/2$, but less than $3\lambda/2$. To eliminate the $H_{2,0}$ and $H_{4,0}$ waves in the horn, the exciting system may be constructed with even symmetry about the horizontal plane

$$y = \frac{a}{2}$$

equidistant between the two upper and lower sides of the horn, as viewed in Fig. 4.

The attenuation constant α may be defined as the logarithmic rate of decrease of magnitude in the direction of propagation, along the X axis, in Fig. 4. The phase constant β may be defined as the logarithmic change of phase along the said X axis. It is known that, for the $H_{0,m}$ wave,

$$\alpha + i\beta = -\frac{\partial}{\partial \rho} \log E = -\frac{2\pi}{\lambda} \frac{K' \frac{m\pi}{\phi_0} \left(2\pi \frac{\rho}{\lambda}\right)}{K \frac{m\pi}{\phi_0} \left(2\pi \frac{\rho}{\lambda}\right)}$$

where

E represents the electric field intensity,
 $i = \sqrt{-1}$

K represents the Hankel function, or the Bessel function of the third kind,

$$K \frac{m\pi}{\phi_0} = J \frac{m\pi}{\phi_0} - Y \frac{m\pi}{\phi_0}$$

$J \frac{m\pi}{\phi_0}$ represents the Bessel function of the first kind, and

$Y \frac{m\pi}{\phi_0}$ represents the Bessel function of the second kind and the Neumann function, and K' is the derivative of K with respect to the argument

$$2\pi \frac{\rho}{\lambda}$$

The attenuation constant α , of course, is the real part of this expression.

It may be shown that, for small values of ρ , in the attenuation region, approximately,

$$\alpha = \frac{m\pi}{\phi_0 \rho}$$

and in the transmission region, for large values of ρ , approximately,

$$\alpha = \frac{1}{2\rho}$$

The attenuation region is that portion of the horn in which the phase constant β is very small compared to the value $2\pi/\lambda$ for a wave in free space; and the transmission region is that portion of the horn in which the phase constant β is substantially equal to $2\pi/\lambda$.

Fig. 6 is a plot of curves, for the $H_{0,m}$ wave, corresponding to horns of perfect conductivity, measured in terms of c/ω , where c is the velocity of light, and $\omega = 2\pi f$, f being the frequency. The curves will be somewhat steeper in practical horns, but the nature of the curves is the same. The ordinate in these curves is the attenuation constant α , and the abscissa is

$$2\pi \frac{\rho}{\lambda}$$

a measure of the radial distance ρ . The curves of Fig. 6 correspond to different values of

$$\frac{m\pi}{\phi_0} = 1, 3, 5, 7, 9$$

If, for example, $m=1$, corresponding to the $H_{0,1}$ wave, these curves correspond to $\phi_0=180^\circ, 60^\circ, 36^\circ, 25.7^\circ, 20^\circ$.

In Fig. 6, the upper attenuation region, indicated by ATN, is separated by the dotted line from the lower transmission region, indicated by TR. This dotted-line boundary between these two regions, although indefinite, has been taken as the lowest root of

$$Y_{\frac{m\pi}{\phi_0}} \left(2\pi \frac{\rho}{\lambda} \right) = 0$$

The lowest-root solution of this equation will yield ρ_0/λ as a function of $m\pi/\phi_0$:

$$\frac{\rho_0}{\lambda} = f \left(\frac{m\pi}{\phi_0} \right)$$

Two curves, for $m=1$ and $m=3$, representing this cut-off-frequency equation, are, as before stated, plotted in Fig. 5.

$$D_0 = 2\rho_0 \sin \frac{\phi_0}{2} = 2f \left(\frac{m\pi}{\phi_0} \right) \lambda \sin \frac{\phi_0}{2}$$

If this last equation be plotted, with D_0 and ϕ_0 as co-ordinates for different values of m , it will be found that for $m=1$, corresponding to the $H_{0,1}$ wave, D_0/λ is substantially equal to, but a little greater than $\frac{1}{2}$, which indicates that the exciting means 14 should be disposed in the horn in such a place that the horizontal length of the throat of the horn, or the transverse distance, D_0 , is not greatly less than $\lambda/2$, a half wavelength. It is also found from this expression that for $m=3$, corresponding to the $H_{0,3}$ wave, the value D_0/λ is substantially equal to, but a little greater than $\frac{3}{2}$. Therefore, if the exciting means 14 is positioned in the horn at a place where the transverse distance D_0 is as great as $3\lambda/2$, the $H_{0,3}$ wave may be strongly excited. These two conditions, taken together, show that the said transverse dimension D_0 , or the position of the exciting or absorbing means 14 in the horn, should be substantially equal to or slightly greater than $\lambda/2$ but not as great as $3\lambda/2$. In fact, to obtain the greatest amount of attenuation for the $H_{0,3}$ wave, which will result in its substantial elimination for small flare angles ϕ_0 , the transverse distance D_0 should be substantially equal to $\lambda/2$.

More generally, to obtain the $H_{0,m}$ wave and suppress the higher-order waves, the transverse dimension D_0 , or the position of the exciting or absorbing means 14 in the horn, should be substantially between

$$\frac{m\lambda}{2} \text{ and } (m+2)\frac{\lambda}{2}$$

and to obtain the greatest amount of attenuation for the said higher-order waves, which will result in their substantial elimination for small flare angles ϕ_0 , the transverse dimension D_0 , or the position of the exciting or absorbing means 14 in the horn, should be substantially equal to

$$\frac{m\lambda}{2}$$

This provides a suitable design of horn for producing a wave of any desired order and, for sufficiently small flare angles, the elimination of all waves of higher order. For the $H_{0,1}$ wave, for example, the exciting or absorbing means 14

should be positioned, or the hollow pipe 18 should be connected to the horn 16, at the point determined by the equation

$$D_0 = \frac{\lambda}{2}$$

approximately, or a little more or less. To pass the $H_{0,3}$ wave, this distance should be approximately

$$D_3 = \frac{3\lambda}{2}$$

that is, the length of the horn will be at least long enough to pass substantially the $H_{0,3}$ wave. The higher-order waves will thus also be substantially eliminated.

As an illustration, the curve for

$$\frac{m\pi}{\phi_0} = 3$$

20 in Fig. 6, applies to the $H_{0,1}$ wave in a horn having a flare angle $\phi_0=60^\circ$.

The analysis is not rigorous, and it is impossible, with present knowledge, to lay down rigorous rules or exact formulas. The formulas 25 serve merely as a first approximation. Final adjustments must always be made, in practice, under conditions of actual operation. Variations of as much as fifty per cent, and even more, from the mathematical relations deduced theoretically, have been observed, in actual practice.

Though the description above has been specifically with respect to sectoral and slightly pyramidal shapes, the same results may be obtained with a reasonable degree of accuracy, such 35 as is usable in most engineering applications, with horn shapes that resemble the sectoral or slightly pyramidal. For example, the rectangular cross-section of these shapes may be modified slightly to have round instead of square corners, 40 or a more or less flat or other cross-section of substantially the same shape, without altering materially the radiation pattern and the applicability of the design relations of these specifications. It is the intention of this disclosure and 45 the appended claims to include such modifications of the invention within its scope.

In the case of conical horns, for example, the transverse dimension at the throat or the position of the energy-translating means should be 50 substantially equal to or slightly greater than the critical transverse dimension of a hollow pipe of circular cross-section for the corresponding type of wave. In particular, in a horn of the above-described shape, for radiation with the 55 lowest-order transversely polarized wave, H_1 , the diameter at the throat, or where the energy-translating means is positioned, should be substantially equal to or slightly greater than $\lambda/1.7$. Similarly, for horns of other cross-sectional 60 shape, the transverse dimension at the throat or at the position of the energy-translating means may be determined from the critical relation for hollow-pipe waves in a hollow pipe of the same cross-section.

65 Modifications will occur to persons skilled in the art and all such are considered to fall within the scope and spirit of the invention.

What is claimed is:

1. An electromagnetic horn of substantially 70 sectoral shape adapted for the propagation therein of $H_{0,m}$ waves of wave-length λ having a radial component of magnetic intensity but no radial component of electric intensity in the horn, where m is a positive integer, the horn being 75 provided with a pair of oppositely disposed flaring

sides substantially parallel, and a pair of oppositely disposed sides substantially normal, to the lines of electric intensity of the said waves within the horn, the horn having exciting or absorbing means positioned where the transverse dimension of the throat, between flaring sides of the horn, is substantially equal to or greater than substantially $\lambda/2$.

2. An electromagnetic horn of substantially sectoral shape adapted for the propagation therein of $H_{0,m}$ waves of wave-length λ having a radial component of magnetic intensity but no radial component of electric intensity in the horn, where m is a positive integer, the horn being provided with a pair of oppositely disposed flaring sides substantially parallel, and a pair of oppositely disposed sides substantially normal, to the lines of electric intensity of the said waves within the horn, and exciting or absorbing means positioned in the throat of the horn where the transverse dimension of the throat, between the flaring sides of the horn, is substantially equal to or greater than substantially $\lambda/2$.

3. An electromagnetic horn of substantially sectoral shape adapted for the propagation therein of $H_{0,m}$ waves of wave-length λ having a radial component of magnetic intensity but no radial component of electric intensity in the horn, where m is a positive integer, the horn being provided with a pair of oppositely disposed flaring sides substantially parallel, and a pair of oppositely disposed sides substantially normal, to the lines of electric intensity of the said waves within the horn, the horn having a cut-off throat portion the transverse dimension of which, between the flaring sides of the horn, is substantially equal to or greater than substantially $\lambda/2$.

4. An electromagnetic horn of substantially sectoral shape adapted for the propagation therein of the lowest order, $H_{0,1}$, waves of wave-length λ having a radial component of magnetic intensity but no radial component of electric intensity in the horn, the horn being provided with a pair of oppositely disposed flaring sides substantially parallel, and a pair of oppositely disposed sides substantially normal, to the lines of electric intensity of the said waves within the horn, the horn having exciting or absorbing means positioned where the transverse dimension of the throat, between flaring sides of the horn, is between substantially $\lambda/2$ and $3\lambda/2$.

5. An electromagnetic horn of substantially sectoral shape adapted for the propagation therein of the lowest order, $H_{0,1}$, waves of wave-length λ having a radial component of magnetic intensity but no radial component of electric intensity in the horn, the horn being provided with a pair of oppositely disposed flaring sides substantially parallel, and a pair of oppositely disposed sides substantially normal, to the lines of electric intensity of the said waves within the horn, and exciting or absorbing means positioned in the throat of the horn where the transverse dimension of the throat, between the flaring sides of the horn, is between substantially $\lambda/2$ and $3\lambda/2$.

6. An electromagnetic horn of substantially sectoral shape adapted for the propagation therein of the lowest order, $H_{0,1}$, waves of wave-length λ having a radial component of magnetic intensity but no radial component of electric intensity in the horn, the horn being provided with a pair of oppositely disposed flaring sides substantially parallel, and a pair of oppositely disposed sides substantially normal, to the lines of electric intensity of the said waves within the

horn, the horn having a cut-off throat portion the transverse dimension of which, between the flaring sides of the horn, is between substantially $\lambda/2$ and $3\lambda/2$.

5. An electromagnetic horn of substantially sectoral shape adapted for the propagation therein of $H_{0,m}$ waves of wave-length λ having a radial component of magnetic intensity but no radial component of electric intensity in the horn, where m is a positive integer, the horn being provided with a pair of oppositely disposed flaring sides substantially parallel, and a pair of oppositely disposed sides substantially normal, to the lines of electric intensity of the said waves within the horn, the horn having exciting or absorbing means positioned where the transverse dimension of the throat, between the flaring sides of the horn, is between substantially

$$20 \quad m\frac{\lambda}{2} \text{ and } (m+2)\frac{\lambda}{2}$$

8. An electromagnetic horn of substantially sectoral shape adapted for the propagation therein of $H_{0,m}$ waves of wave-length λ having a radial component of magnetic intensity but no radial component of electric intensity in the horn, where m is a positive integer, the horn being provided with a pair of oppositely disposed flaring sides substantially parallel, and a pair of oppositely disposed sides substantially normal, to the lines of electric intensity of the said waves within the horn, and exciting or absorbing means positioned in the throat of the horn where the transverse dimension of the throat, between the flaring sides of the horn, is between substantially

$$35 \quad m\frac{\lambda}{2} \text{ and } (m+2)\frac{\lambda}{2}$$

9. An electromagnetic horn of substantially sectoral shape adapted for the propagation therein of $H_{0,m}$ waves of wave-length λ having a radial component of magnetic intensity but no radial component of electric intensity in the horn, where m is a positive integer, the horn being provided with a pair of oppositely disposed flaring sides substantially parallel, and a pair of oppositely disposed sides substantially normal, to the lines of electric intensity of the said waves within the horn, the horn having a cut-off throat portion the transverse dimension of which, between the flaring sides of the horn, is between substantially

$$50 \quad m\frac{\lambda}{2} \text{ and } (m+2)\frac{\lambda}{2}$$

10. An electromagnetic system having, in combination, an electromagnetic horn adapted for the propagation therein of waves of a predetermined wave-length and having a small throat end and a large mouth end, and means for producing waves of the said wave length of a predetermined order and excluding waves of higher order comprising absorbing or exciting means positioned in the throat where the transverse dimension of the throat is substantially equal to or only slightly greater than the critical transverse dimension of a hollow pipe that will pass waves of the said wave-length.

11. An electromagnetic horn of substantially sectoral shape adapted for the propagation therein of $H_{0,m}$ waves of wave-length λ having a radial component of magnetic intensity but no radial component of electric intensity in the horn, where m is a positive integer, the horn being provided with a pair of oppositely disposed flaring sides substantially parallel, and a pair of oppositely

disposed sides substantially normal, to the lines of electric intensity of the said waves within the horn, the horn having exciting or absorbing means positioned where the transverse dimension of the throat, between the flaring sides of the horn, is greater than a value within about fifty per cent of substantially $\lambda/2$.

12. An electromagnetic horn of substantially sectoral shape adapted for the propagation therein of $H_{0,m}$ waves of wave-length λ having a radial component of magnetic intensity but no radial component of electric intensity in the horn, where m is a positive integer, the horn being provided with a pair of oppositely disposed flaring sides substantially parallel, and a pair of oppositely disposed sides substantially normal, to the lines of electric intensity of the said waves within the horn, and exciting or absorbing means positioned in the throat of the horn where the transverse dimension of the throat, between the flaring sides of the horn, is greater than a value within about fifty per cent of substantially $\lambda/2$.

13. An electromagnetic horn of substantially sectoral shape adapted for the propagation therein of $H_{0,m}$ waves of wave-length λ having a radial component of magnetic intensity but no radial component of electric intensity in the horn, where m is a positive integer, the horn being provided with a pair of oppositely disposed flaring sides substantially parallel, and a pair of oppositely disposed sides substantially normal, to the lines of electric intensity of the said waves within the horn, the horn having a cut-off throat portion the transverse dimension of which, between the flaring sides of the horn, is greater than a value within about fifty per cent of substantially $\lambda/2$.

14. An electromagnetic horn of substantially sectoral shape adapted for the propagation therein of the lowest order, $H_{0,1}$, waves of wave-length λ having a radial component of magnetic intensity but no radial component of electric intensity in the horn, the horn being provided with a pair of oppositely disposed flaring sides substantially parallel, and a pair of oppositely disposed sides substantially normal, to the lines of electric intensity of the said waves within the horn, the horn having exciting or absorbing means positioned where the transverse dimension of the throat, between flaring sides of the horn, is within about fifty per cent of a value between substantially $\lambda/2$ and $3\lambda/2$.

15. An electromagnetic horn of substantially sectoral shape adapted for the propagation therein of the lowest order, $H_{0,1}$, waves of wave-length λ having a radial component of magnetic intensity but no radial component of electric intensity in the horn, the horn being provided with a pair of oppositely disposed flaring sides substantially parallel, and a pair of oppositely disposed sides substantially normal, to the lines of electric intensity of the said waves within the horn, and exciting or absorbing means positioned in the throat of the horn where the transverse dimension of the throat, between the flaring sides of the horn, is within about fifty per cent of a value between substantially $\lambda/2$ and $3\lambda/2$.

16. An electromagnetic horn of substantially sectoral shape adapted for the propagation therein of the lowest order, $H_{0,1}$, waves of wave-length λ having a radial component of magnetic intensity but no radial component of electric intensity in the horn, the horn being provided with a pair of oppositely disposed flaring sides substantially

parallel, and a pair of oppositely disposed sides substantially normal, to the lines of electric intensity of the said waves within the horn, the horn having a cut-off throat portion the transverse dimension of which, between the flaring sides of the horn, is within about fifty per cent of a value between substantially $\lambda/2$ and $3\lambda/2$.

17. An electromagnetic horn of substantially sectoral shape adapted for the propagation therein of $H_{0,m}$ waves of wave-length λ having a radial component of magnetic intensity but no radial component of electric intensity in the horn, where m is a positive integer, the horn being provided with a pair of oppositely disposed flaring sides substantially parallel, and a pair of oppositely disposed sides substantially normal, to the lines of electric intensity of the said waves within the horn, the horn having exciting or absorbing means positioned where the transverse dimension of the throat, between the flaring sides of the horn, is within about fifty per cent of a value between substantially

$$m\frac{\lambda}{2} \text{ and } (m+2)\frac{\lambda}{2}$$

18. An electromagnetic horn of substantially sectoral shape adapted for the propagation therein of $H_{0,m}$ waves of wave-length λ having a radial component of magnetic intensity but no radial component of electric intensity in the horn, where m is a positive integer, the horn being provided with a pair of oppositely disposed flaring sides substantially parallel, and a pair of oppositely disposed sides substantially normal, to the lines of electric intensity of the said waves within the horn, and exciting or absorbing means positioned in the throat of the horn where the transverse dimension of the throat, between the flaring sides of the horn, is within about fifty per cent of a value between substantially

$$m\frac{\lambda}{2} \text{ and } (m+2)\frac{\lambda}{2}$$

19. An electromagnetic horn of substantially sectoral shape adapted for the propagation therein of $H_{0,m}$ waves of wave-length λ having a radial component of magnetic intensity but no radial component of electric intensity in the horn, where m is a positive integer, the horn being provided with a pair of oppositely disposed flaring sides substantially parallel, and a pair of oppositely disposed sides substantially normal, to the lines of electric intensity of the said waves within the horn, the horn having a cut-off throat portion the transverse dimension of which, between the flaring sides of the horn, is within about fifty per cent of a value between substantially

$$m\frac{\lambda}{2} \text{ and } (m+2)\frac{\lambda}{2}$$

20. An electromagnetic system having, in combination, an electromagnetic horn adapted for the propagation therein of waves of a predetermined wave-length and having a small throat end and a large mouth end, and means for producing waves of the said wave-length of a predetermined order and excluding waves of a higher order comprising a cut-off throat portion provided upon the throat end and the transverse dimension of which is substantially equal to or only slightly greater than the critical transverse dimension of a hollow pipe that will pass waves of the said wave-length.

WILMER L. BARROW.
